COAL CUTTING, BREAKING, AND LOADING
MINING MACHINENils D. Levin, Columbus, Ohio, assignor to The
Jeffrey Manufacturing Company, a corporation
of Ohio

Application March 19, 1947, Serial No. 735,751

1 Claim. (Cl. 262—9)

1

This invention relates to a combination cutting, breaking and loading machine which is adapted to cut, break, gather and load coal, the cutting, breaking and gathering taking place at the face of a mine room, the loading being into a mine car, buggy or the like.

An object of the invention, therefore, is to provide an improved mining machine of the above general type.

Another object of the invention is to provide a mining machine capable of cutting, breaking and gathering coal, which is extremely flexible in operation and includes mechanism for making a bottom kerf in solid coal and an additional or supplemental mechanism for mining which bores and breaks down solid coal above the bottom kerf.

Another object of the invention is to provide an improved mining machine capable of cutting, breaking and gathering solid coal, which is extremely flexible in operation and includes a bottom kerf cutter and conveyer adapted to cut a bottom kerf and to convey loose and/or broken coal rearwardly in combination with one but preferably two spaced kerf cutters adapted to cut an upright kerf or spaced kerfs above the bottom kerf and a power operated drill and expansion device for breaking down the solid coal above the bottom kerf whereby the broken coal will be conveyed rearwardly by the bottom kerf cutter and conveyer.

In carrying out the foregoing object it is another object of the invention to provide an improved mining machine as set forth wherein the upright kerf cutters carry power driven endless kerf cutter chains and are pivoted for upright swinging movement wherein there is preferably provided means for controlling the operation at least of one of said kerf cutter chains independently of the others.

Another object of the invention is to provide an improved mining machine capable of cutting, breaking and gathering solid coal, which is extremely flexible in operation and includes a bottom kerf cutter and a conveyer adapted to cut a bottom kerf and to convey loose and/or broken coal rearwardly and to provide a conveyer adjacent the rear portion of the bottom kerf cutter and conveyer means for co-operating with the latter in conveying loose and/or broken coal rearwardly thereover.

Another object of the invention is to provide an improved coal cutting, breaking and loading machine including an endless chain kerf cutter and conveyer adapted to cut a bottom kerf and

2

to convey loose and/or broken coal rearwardly thereover wherein an endless chain conveyer cooperates with the rear portion of said endless chain bottom kerf cutter and conveyer to convey coal thereover, the bottom kerf cutter and conveyer and the co-operating conveyer both being divided and mounted for swinging adjustment about a horizontal axis with at least one of them including automatic means for adjusting the length of its chain guide means when adjusted to different positions about the horizontal axis.

Another object of the invention is to provide an improved coal cutting, breaking and loading machine including a kerf cutter and conveyer adapted to cut a bottom kerf and to convey loose and/or broken coal rearwardly either with or without additional or supplemental kerf cutter means, but with a power operated drill and expansion device adapted to bore and break by expansion solid coal above the bottom kerf cutter and conveyer, the power operated drill and expansion device being preferably mounted for vertical swinging adjustment at various angles above the bottom kerf cutter and for rectilinear feeding movement.

A further object of the invention is to provide a very flexible combination mining and loading machine which has traction mechanism adapted to produce reverse and swinging movements of the mining machine and in which coal is cut and gathered by a combination cutting and gathering mechanism and is delivered rearwardly by a discharge conveyer preferably having a laterally swinging boom.

Another object of the invention is to provide an improved rotary drill and expansion device for boring and breaking solid coal by expansion.

Still another object of the invention is to provide an improved power means for driving a rotary drill and hydraulic expansion means.

Other objects of the invention will appear hereinafter, the novel features and combinations being set forth in the appended claim.

In the accompanying drawings, Figs. 1 and 2 placed end to end constitute a side view largely in section, though partly in elevation, of the combination cutting, breaking and loading machine comprising the invention;

Fig. 3 is a perspective view of the machine of Figs. 1 and 2, with parts in section;

Fig. 4 is a side view in elevation of the machine shown in Fig. 3, with a portion of a mine room in which the machine is operating shown in phantom;

Fig. 5 is a detail view in section, showing the operating mechanism for the main clutch;

Fig. 6 is a sectional view taken on the line 6—6 of Fig. 1, looking in the direction of the arrows;

Fig. 7 is a sectional view taken on the line 7—7 of Fig. 1, looking in the direction of the arrows;

Fig. 8 is a sectional view taken on the line 8—8 of Fig. 2, looking in the direction of the arrows, some parts being omitted in the interest of clearness;

Fig. 9 is a sectional view taken on the line 9—9 of Fig. 2 of the drawings, looking in the direction of the arrows, with parts omitted;

Fig. 10 is a sectional view taken on the line 10—10 of Fig. 2 of the drawings, looking in the direction of the arrows, with parts omitted;

Fig. 11 is a sectional view taken on the line 11—11 of Fig. 2 of the drawings, looking in the direction of the arrows;

Fig. 12 is a fragmentary sectional view through the bottom kerf cutter and conveyer mechanism of the mining machine, some parts being omitted in the interest of clearness, the view being taken on a vertical plane upon which line 12—12 of Fig. 3 lies;

Fig. 13 is a view partly in section and partly in elevation of a rotary drill and hydraulic expansion coal mining tool of the machine;

Fig. 14 is a view in horizontal section of the motor for carrying and driving the tool seen in Fig. 13, some parts being omitted in the interest of clearness; and

Fig. 15 is a piping diagram of the hydraulic system of the invention.

This invention is an improvement upon the machine shown and described by Sterling C. Moon in his co-pending application Serial No. 475,274 filed February 9, 1943, entitled "Cutting and Loading Machine," now abandoned, and follows the structure thereof except for differences shown or described.

Referring to the accompanying drawings, the combination mining, breaking and loading machine of the invention includes a main frame 20 which is formed by a pair of longitudinally extending spaced-apart main frame plates 21, 21 (see Figs. 6 to 11, inclusive). These longitudinally extending main frame plates 21, 21 are connected together by a number of transversely extending plates, for example, there is a transversely extending sloping top plate 22 which is seen in Figs. 1, 2 and 9 of the drawings, which extends between the plates 21, 21 and is rigidly attached thereto by welding along the edges of said sloping top plate 22. This plate 22 may be considered as the principal top plate interconnecting the main frame plates 21, 21 to form the main frame 20.

There is also a main bottom plate which is substantially horizontal and which is seen at 23 in Figs. 1 and 2 of the drawings, and this bottom plate is also seen in Figs. 6 and 7 of the drawings. As clearly seen in Figs. 1, 2, 6 and 7, the bottom plate 23 is actually fabricated from a number of plates which are welded together, this fabrication being done to provide clearance for certain gearing contained within the housing which is formed by the main frame 20.

Adjacent the rear end of the housing or main frame 20 there is a removable transversely extending top plate 24, best seen in Figs. 1 and 6 of the drawings, this plate being removable to permit access to the mechanism contained within the housing formed by said main frame 20. The rear end of the main frame or housing 20 is

formed by an upright transversely extending rear plate 25, best seen in Fig. 1 of the drawings. The forward end of the main frame or housing 20 is also provided with an upright transversely extending front plate 26, best seen in Fig. 2 of the drawings. Various other plates which constitute integral portions of the main frame 20 are described hereinafter.

The main frame 20 also contains lateral extensions which provide support for traction means preferably in the form of endless or crawler tracks and also provide support for certain other mechanism as hereinafter described. One of these extensions is seen at 27 in Fig. 3 of the drawings, said extensions being clearly visible, at least in part, in a number of the other figures of drawings, including Figs. 6 to 11, inclusive.

The mining machine is generally similar on the two opposite sides and consequently there is

20 an extension 28 on the left-hand side of the machine as it is viewed in several figures, which is similar to the extension 27. Extensions 27 and 28 being similar in construction, a description of one will suffice for the two. As seen, for example, in Figs. 3 and 9 of the drawings, there is an outer or extension plate 29 which extends substantially upright, and this extension plate 29 is connected to the adjacent main frame plate 21 by a number of transverse plates, one of which is seen at 30 in Fig. 9 of the drawings.

30 The main frame 20 is mounted on a pair of crawlers or endless chain traction devices 31, 32 which are of similar construction, the crawler 31 being on the right-hand side of the vehicle 35 as viewed in the drawings, and the crawler 32 being on the left-hand side thereof. Since these crawlers 31, 32 are of similar construction, a description of one will suffice for both. Said crawler 31 includes an endless chain 33 which supports the main frame 20 through a plurality of rollers 34 which are mounted upon journal bearings and extend outwardly from the adjacent frame member 21 toward the outer plate 29, as clearly illustrated in Fig. 7 of the drawings. The outer ends of the supporting shafts for the rollers 34 are carried by a longitudinally extending plate 45 35 which is welded to top and bottom plates, clearly illustrated in Fig. 7 of the drawings, which in turn are welded to the main frame 50 plate 21 and outer plate 29.

As clearly illustrated in Fig. 2 of the drawings, the rollers 34 do not extend the full length of the main frame 20, and forwardly of the last of said rollers 34 there is a U-shaped wear shoe 55 36 (see Fig. 11) adjacent said forward end of the main frame 20 over which the top of the lower run of the chain 33 travels. Since this portion of the lower run of the chain is normally out of engagement with the ground, there

60 will not be excessive friction due to this sliding relation between the chain 33 and the shoe 36. The foremost portion of the endless chain 33 is preferably mounted upon a take-up idler roller not illustrated, which can be adjusted to maintain proper tension on said chain 33. The upper or return run of the chain 33 is supported in part upon an idler roller 37 (see Fig. 11) which is journaled to a bracket 38 which in turn is bolted to main frame plate 21, the roller 37 having a removable retaining cap 39 which is attached by screws to the journal neck of the bracket 38. The principal portion of the return run of the chain 33 is slidably supported on a 70 supporting plate 40 (see Figs. 7, 8 and 9), which

plate 40 is supported from the adjacent main frame plate 21.

A longitudinally extending cover plate 41 (see Fig. 8) is provided which co-operates with the plate 40 substantially to enclose the return run of said chain 33. The mechanism for driving the crawlers will be described in detail hereinafter.

Extending rearwardly from the main body of the main frame 20 and rigidly attached thereto as by welding, consequently forming an integral part thereof, is a rear platform 42 (see Figs. 1 and 4). Mounted upon the platform 42 is an electric motor 43.

Adjacent its forward end the machine is provided with what is essentially a pair of spaced-apart cutter bars 44, 45, which cutter bars have the double function of cutting a deep bottom kerf in solid coal and conveying the loose coal rearwardly to the receiving end of a receiving, discharge or elevator conveyer designated generally by the reference character 46, the structure of which is described hereinafter more completely.

The cutter bars 44 and 45 are divided and have their rear ends mounted upon a common transversely extending sloping plate 47 (see Figs. 2 and 11), which plate 47 is welded to the main frame plates 21 as well as to the extensions 27 and 28 including the plate 29 of the former. As a consequence, the rear ends of the cutter bars 44 and 45 are connected as a unit, and as clearly seen in Fig. 11 of the drawings, said cutter bars 44 and 45 have their bottoms spaced above the plate 47 by means of spacer plates 48 so that a coal conveying trough or way 49 is formed between the two cutter bars 44 and 45, said plate 47 forming a bottom for said trough or way at the rear portion thereof.

While the rear portion or section of each of the cutter bars 44 and 45 is stationary with respect to the main frame 20, the principal or front portion of each of said cutter bars, including the central upwardly sloping portion and the front generally horizontal portion, is pivotally mounted as a unit about a horizontal axis so that the central and forward portions of said cutter bars 44 and 45 can be swingably adjusted about said horizontal axis, thus adjusting the position of the bottom kerf cut by the cutter bars 44 and 45.

The pivotal mounting of said central and forward portions of the cutter bars 44 and 45 is provided by spaced pivot joints between a common bottom plate frame member 50 (see Figs. 2, 3, 4 and 12) which rigidly and permanently connects the central portions of the cutter bars 44 and 45 and which is provided with pivot arms, one of which is seen at 51 in Fig. 3 of the drawings, which are pivoted to the frame extensions 27, 28, the pivotal connection to the plate 29 of frame extension 27 being seen at 52 in Fig. 3 of the drawings, there being a similar connection between the plate 50 and extension 28, seen at 52' in Fig. 4.

The bottom plate 50 not only permanently connects the central portions of the cutter bars 44 and 45 together but it also forms a bottom plate for the trough 49 which trough extends not only adjacent the stationary portion of the cutter bars 44 and 45, as illustrated in Fig. 11 of the drawings, but also extends adjacent the rear portions of the cutter bars 44 and 45 which are permanently connected together, as clearly illus-

trated in Fig. 3 of the drawings; the bottom plates of said cutter bars 44 and 45 being spaced above the plate 50 by spacer plates 53 similar to the above described spacer plates 48.

In other words, each of the cutter bars 44 and 45 is provided with a rear portion which is rigidly connected to the main frame 20 while the central and forward portions thereof are pivotally mounted as a unit about a horizontal axis, thereby permitting swinging adjustment thereof with respect to said main frame 20. In addition and as clearly illustrated in Fig. 3 of the drawings, each of the cutter bars 44 and 45 is preferably provided with a forward adjustable shoe to adjust the tension of the combination kerf cutting and conveying chain associated therewith, there being such a chain 54 associated with the cutter bar 44 and such a chain 55 associated with the cutter bar 45.

The endless cutter chains 54 and 55 are of similar structure but they travel orbitally in opposite directions, the former clockwise, the latter counterclockwise, and each includes a plurality of removable cutter bits, those of the chain 54 being seen at 56. The bits 56 are fanned out in a conventional manner and are effective not only to cut a kerf at the bottom or floor of the mine room as the entire machine is fed forwardly, but in addition they act to convey material along the trough 49 and discharge it to the receiving, discharge or elevator conveyer 46. It is, of course, evident, particularly by reference to Fig. 2 of the drawings, that the trough 49 is bottomless adjacent the forward portion wherein the cutter bars 44 and 45 are substantially horizontal. Under the bottomless forward portion the mine floor will form the effective bottom of the trough through which the material is conveyed until it reaches the plate 50 over which it will travel to the stationary plate 47 until discharged. The driving mechanism for the cutter chains 54 and 55 is described in detail hereinafter.

Pivotal movement of the pivoted part of the two cutter bars 44 and 45 which are connected together as a unit, is provided by a hydraulic piston motor 58, the cylinder of which is pivotally attached to a bracket which is positioned adjacent the forward end of the main frame 20 and just forward of the front plate 26 thereof, as clearly seen by reference to Fig. 2 of the drawings, the piston of said motor 58 being pivotally attached to a pivot pin 59 carried in a bracket formed on the bottom plate 50. It is obvious that the bottom plate 50 and those parts rigidly attached to it, including the two cutter bars 44 and 45, and other associated parts to be herein-after described, constitute a supplemental or auxiliary frame which is pivotally attached to the main frame 20 and is swingable with respect thereto about a horizontal axis.

It may also be mentioned that since a portion of the cutter bars 44 and 45 is swingable with respect to another portion, the cutter chains 54 and 55 are of the universal type. This is also required by the fact that the two cutter bars 44 and 45 do not lie in a single horizontal plane.

Mounted upon the upwardly sloping portions of the spaced cutter bars 44 and 45 and in stacked relation therewith are a pair of endless chain conveyers, the endless chain conveyer above the cutter bar 44 being indicated generally at 265 and the conveyer above the cutter bar 45 being indicated generally at 266 (see Figs. 3 and 11). The endless chain conveyers 265 and 266 each includes an orbitally moving endless chain, links

of which include outwardly extending portions or flights adapted to co-operate with those portions of the kerf cutter and conveyer chains 54 and 55 which are moving rearwardly in the way 48 and with each other in conveying loose and/or broken coal upwardly rearwardly in and along the way and for discharging it therefrom to the receiving end of the receiving, discharge or conveyer elevator 46. Since the structure of the endless chain conveyers 265 and 266 is similar, a description of conveyer 265 (seen in Figs. 2, 3, 11 and 12) will suffice for both conveyers.

Referring now to Figs. 11 and 12, endless chain conveyer mechanism 265 includes a divided endless chain guide structure 267 having a rear portion or section 268 and a front portion or section 269. Rear portion 268 of guide structure 267 is carried directly by the rear portion of cutter bar 44 which is mounted upon sloping main frame plate 47. The rear portion of the cutter bar chain guide and rear portion 268 of the conveyer chain guide are similar in construction and the rear portion of the cutter bar chain guide, as previously described, is spaced above the sloping main frame plate 47 by spacers 48. The rear portion of the cutter bar 44 is a hollow structure including a bottom plate 270 supported by the spacers 48 and cross spacers 271, inwardly spaced upright side wall members 272, cross spacer 273 and a top plate 274. Top plate 274, bottom plate 270 and the upright side wall members 272 co-operate to form chain guide channels in opposite sides of the cutter bar rear section in which the kerf cutter and conveyer chain 54 operates and chain guide wear strips 275 are secured to both top and bottom plates 274 and 270 for guiding the kerf cutter and conveyer chain 54 along the channels. The members of the rear portion of the cutter bar 44 are secured together and to the sloping main frame plate 47 by a plurality of bolts.

A pair of upright spacer members 276 are carried by top plate 274 of the rear portion of the cutter bar 44 and are secured thereto by a plurality of bolts 277 which extend through the top wear strips 275, the top plate 274 and are threaded into the upright spacer members 276. These upright spacer members 276 together with cross spacers 278 welded to the top plate 274 carry the rear portion 268 of the endless chain conveyer guide 267 and function to deepen the conveyer trough or way 49 above the kerf cutter and conveyer chains 54 and 55.

The rear portion 268 of divided endless guide 267 includes a bottom plate 279, spaced upright side wall members 280, a cross member 281 welded to the bottom plate 279, and a top plate 282 which, like the members of the rear portions of the cutter bar, co-operate to form conveyer chain guide channels in opposite sides of the rear conveyer chain guide portion 268 and in which conveyer chain guiding wear strips 283 are provided for guiding the endless chain of conveyer 265. The bottom plate 279 is bolted to the upright spacers 276 by bolts 284 that extend through the bottom wear strips 283, and to the cross spacers 278 by bolts 284' (see Fig. 11). The forward ends of both of the top plates 274 and 282 as well as both of the bottom plates 270 and 279 are bent to form tapered chain guide sections at the forward end of chain guide portion 268.

The construction of the forward or principal portion of each of the cutter bar chain guides is similar to that of the described rear portions thereof and, as set forth previously, the front or principal portions of the cutter bars 44 and

45 include a common bottom plate 50 which rigidly and permanently connects and spaces them apart and by which they are pivoted to the main frame 20 and consequently to their rear portions for swinging adjustment about a horizontal axis, the axis extending through the centers of the pivotal connections indicated at 52 in Figs. 3 and 12 and at 52' in Fig. 4.

Referring particularly to Fig. 12, the horizontal axis about which the principal portion of the cutter bars is adjustable is indicated at 284 and lies just forward of the rear cutter bar portion and it forms or lies at the intersection of horizontal planes taken centrally through the height 10 of the conveyer chain guide channels of both the rear portion and the central portion of the cutter bars 44 and 45. Thus the distance between the front and rear portions of the cutter bars taken along the mentioned planes will remain 15 constant for all swinging adjustments of the principal portion of the cutter bars about the axis 284.

Mounted in stacked relation with and above the rear upwardly sloping portion of the front or principal section of the cutter bar 44 is the front or forward portion 269 of the conveyer chain guide 267 of the endless chain conveyer 265. Portion 269 of the conveyer chain guide 267 is spaced above the top plate 285 of the central portion of the cutter bar 44 by a generally 25 rectangular frame including a rear cross spacer member 286, a front cross spacer member 287, and a pair of side spacer members 288 welded to the top plate 285 of the cutter bar 44. The

30 rectangular frame including side spacer members 288, like upright spacer members 276, functions to deepen the conveyer trough or way 49 above the kerf cutter and conveyer chains 54 and 55. Spanning and secured to the side spacer 35 members above the rear cross spacer member 286 and bolted to the latter is a fixed bottom plate member 289 to which there is welded an upright cross member 290 which with a pair of upright side spacer members 291 supports a top plate 292. Side members 291 like side members 280

40 of rear portion 268 of the chain guide 267 co-operate with the top and bottom plates 289, 292 to form oppositely disposed conveyer chain side 45 guide channels and the top and bottom plates 289, 292 have their rear ends bent to form tapering chain guide portions at the rear of portion 269. Each plate 289, 292 carries a chain guiding wear strip 293. The spaced upright side 50 members 288 are notched to receive a bed plate 294 which is bolted thereto and extends forwardly over the top of front spacer member 287.

55 A boxlike front or nose structure 295 is carried for forward and rearward rectilinear movement upon the bed plate 294. Boxlike structure 295 includes a bottom plate 296, a rear upright cross spacer member 297, a front upright cross spacer member 298, a pair of upright side wall members 299 and a top plate 300. Side wall members 299 and front spacer 298 co-operate with plates 300 and 296 to form a continuous chain guide 60 channel extending along the opposite sides and the front of the boxlike structure 295.

65 It is to be noted that the front ends of the boxlike structure of both of the endless chain conveyers 265 and 266 are blunt or flat at their forward ends with rounded corners (see Fig. 3) in order that the endless chains of conveyers 265 and 266 which operate orbitally in the guide channels and travel in the same directions as 70 the kerf cutter and conveyer chains 54 and 55

will have a sweeping gathering motion over a broad front and will convey loose and/or broken coal above the bottom kerf cutter element and on the kerf cutter bars 44 and 45 to the center of the bottom kerf cutting element where said material will be caused to enter the deepened conveyer trough or way 49 above and between the kerf cutter bars 44 and 45, the loose coal being conveyed rearwardly therein and discharged into the receiving, discharge, or elevator conveyor 46, conveyers 265, 266 aiding the uphill travel of coal.

Referring again to Fig. 12, because the rear member 268 of divided endless conveyer chain guide 267 is stationarily mounted above and in stacked relation with the rear portion of the cutter bar 44 and the front portion 269 thereof is mounted to the front or principal portion of the cutter bar 44 in a similar manner, the distance between the front and rear ends of the chain guide members 267 taken in planes through the chain guide channels thereof will change as the front or principal portion of the cutter bar 44 is adjusted about horizontal axis 264. It is necessary to maintain the ends of the conveyer guide members a constant distance apart during adjustment and in all adjustment positions of the principal portion of the bottom kerf cutter bar 44 about axis 264. To this end the bottom plate 296 of boxlike structure 295 is slotted at 301 to receive a pair of headed pins 302 that are threaded through bed plate 294 and locked therein by nuts. Slot 301 together with headed pins 302 provide for guided forward and rearward movement of the boxlike structure 295 on bed plate 294 while maintaining the structure in alignment with the rear side chain guide channels of the forward guide member 269.

The top plate supporting and spacer member 290 has on its front side a boss 303 and the rear upright spacer 297 of boxlike member 295 has upon its rear surface or face a boss 304 that is in alignment with the boss 303. Bosses 303 and 304 receive the opposite ends of a heavy compression spring 305 which functions to urge boxlike structure 295 forwardly against the chain of conveyer 265. The chain limits the forward movement of the boxlike structure and the spring 305 maintains it under tension. A plate 426 closes the space between the top plates 292 and 300 above the spring 305. Preferably a divided peaked shield 57 is provided above each of the conveyors 265 and 266, the primary function of which is to direct coal which tends to accumulate thereabove into the central conveyer trough or way 49. The endless chain of conveyer 265 operates over and is driven by a sprocket 308 at the rear of chain guide section 268 and kerf cutter chain 54 operates over a sprocket 164 (see Figs. 10 and 12). Sprockets 308 and 164 are formed upon a common hub and are of equal diameters in order that the endless chains of conveyer 265 and the endless kerf cutter and conveyer chains 54 will be driven in the same direction at equal speeds. If desired suitable covers 306 and 307 may be provided (see Fig. 4) for housing the outside forwardly moving runs of both endless conveyer chains of conveyers 265 and 266 as well as both kerf cutter and conveyer chains 54 and 55.

The mining machine thus far described, except for the additional endless chain conveyers 265, 266 which form a part of the present invention, is identical to the machine described by Sterling C. Moon in his application, Serial No. 475,274, previously set forth.

Another important feature of this invention is the provision of a pair of spaced endless chain type shear kerf cutter bars 309 and 310 (see Figs. 3 and 4) carried pivotally at the forward end of the main frame 20, spaced one at each side thereof for swinging movement about a horizontal axis, and extending forwardly from the main frame 20 above the bottom kerf cutter element for cutting spaced upright or shear kerfs in solid coal above and connecting with the sides of a bottom kerf which has been cut by the bottom kerf cutter element.

The construction of the upright kerf cutter bars 309 and 310 as well as the pivotal mounting 15 and driving means therefor are similar, and therefore a description of cutter bar 310 will suffice for both of the cutter bars. The main frame 311 of upright kerf cutter bar 310 is a welded boxlike arm structure including an inside main plate 312, an outside plate 313, and a pair of oppositely disposed top and bottom spacer strips 314 welded between plates 312 and 313 and co-operating with the latter to provide endless kerf cutter chain guide channels in the 20 top and bottom edges thereof. Suitable chain guiding wear strips are provided in these channels (see Fig. 3). The forward end of the main frame 311 carries a nose portion 315, seen in Fig. 4, that telescopes therewith and is adjustable therein to tension properly the endless kerf cutter chain 316 which operates in the chain guide channels and over the nose portion 315.

Inside main frame plate 312 includes or has connected to it a rearwardly extending portion 35 or tongue 317 by which it is pivotally supported (see Fig. 10) and to which an inner plate 318 of a cutter bar swinging and cover structure 319 is welded. Tongue 317 is pivotally carried through a hub assembly 320 that is a part of 40 the main frame 20 of the mining machine. Hub assembly 320 includes a shoulder ring 321 welded along its edge to the outer extension plate 29 of main frame 20, a disc 322 welded to ring 321 having a central opening 323 in which there is a 45 bearing holder 324, and a tubular housing 325 extending inwardly axially from about the central opening 323 welded to the inner side of the disc 322. The inner end of tubular housing 325 includes a bearing holder 326 and is connected 50 to the main plate 21 of main frame 20 by a welded assembly including plates 327, 328 and a shoulder member 329. A slotted sloping cover 330 is welded at its upper edge to plate 327 and at 55 its lower edge to the top of housing 325. Housing 325 beneath the slot in cover 330 carries a lubricant fitting through which lubricant may be introduced into the housing 325.

Tongue 317 of cutter bar 310 is carried for 60 swinging movement upon the shoulder ring 321 and disc 322 of the hub assembly 320 through a renewable collar bearing 331, the outer ring 332 of which is, for the most part, carried upon a shoulder disc 333 bolted directly to disc 322. Cutter bar swinging and cover structure 319 includes a pair of depending spaced arms 334 and 335 the latter of which is an integral part of plate 318 (see Fig. 3). At the bottom and between the arms 334 and 335 the end of a piston rod 336 of a double acting hydraulic cylinder type 65 motor 337 is pivoted. The double acting hydraulic motor 337 is positioned rearwardly of the arms 334 and 335 and below an operator's platform or step 338 formed by the main frame 20 and is pivotally mounted to the latter at its rear 70 end through a bracket 339. It will be obvious 75

that as the hydraulic motor 337 is expanded its piston rod 336 will move outwardly to rotate the cutter bar structure 310 in a counter-clockwise direction as seen in Fig. 3 upon the hub assembly 320 to raise, pivot or swing the cutter bar 310 in an upright plane or about the central axis of the hub assembly 320 and that as the hydraulic motor 337 is contracted the cutter bar 310 will be lowered or swung in a counter-clockwise direction. Cutter bar 308 is swung by hydraulic motor 337.

Extending through the tubular housing 325 is a stepped cutter chain drive shaft 340. Adjacent its outer end the drive shaft 340 carries an anti-friction bearing 341 which is received by the bearing retaining holder 324 of disc 322. The inner end of drive shaft 340 carries an anti-friction bearing 342 which is received by the inner bearing retaining holder 326 at the inner end of the housing 325. The inner end of drive shaft 340 carries a bevel gear 343 keyed thereto by a key 344 and clamped against bearing 342 by a nut. Bevel gear 343 meshes with a bevel gear 346 keyed to and carried by upright shaft 159 which drives the bottom kerf cutting and conveyor chain sprocket 164 as well as the sprocket 308 of the upper conveyor 265. (The gearing, clutches, etc., connecting shaft 159 to the driving motor 43 are fully discussed hereinafter.)

The outer end of drive shaft 340 carries a flanged disc 347 which co-operates with flanges formed in the collar disc 333 to form a labyrinth-type lubricant seal at the outside of bearing 341. A kerf cutter chain drive sprocket 348 is bearinged for free rotation upon an outer central extension 349 of flanged disc 347 and manually operated clutch mechanism 350 connects the sprocket 348 and shaft 340. By selectively connecting or disconnecting the kerf cutter chain drive sprocket 348 and shaft 340, clutch 350 controls the operation or driving of kerf cutter chain 316 by electric motor 43. The details of clutch 350 are shown at the left-hand side of Fig. 10 of the drawings and this clutch includes a slotted flange 351 formed on the outer end of shaft 340. A suitable locking disc 352 having a plurality of radially spaced sidewardly projecting fingers or lugs 353 which extend through the slots of flange 351 engage fingers or lugs 354 formed as integral parts of the hub of sprocket 348. Locking disc 352 is rotatably carried by a shaft 355 threaded centrally into the outer end of the drive shaft 340 and carrying an outer disc by which the threaded shaft 355 may be rotated manually to withdraw or engage the fingers 353 of the locking disc 352 with the fingers 354 of sprocket 348. A suitable cover 356 for the rear end of kerf cutter chain 316 and drive sprocket 348 is provided, said cover telescoping with a flange of the cutter bar swinging structure 319 and secured thereto by bolts, not shown. Access to locking disc 352 of clutch 350 may be had through an opening 345 in each cover 356.

In addition to providing for the cutting of a bottom kerf, the spaced upright kerfs connecting with the cut bottom kerf, and the conveying rearwardly of coal cut by the kerf cutters as well as coal otherwise fractured, I provide an additional or supplemental mining mechanism 60 which is adapted to drill or bore into solid coal above the bottom kerf cutter between the spaced upright or shear kerf cutters either during or after the said kerfs have been cut and to then break down the coal by expansion. The supplemental mining mechanism 60 includes a sec-

ondary or additional supplemental frame 61 pivoted for swinging movement about a horizontal axis which substantially coincides with the horizontal axis about which shear cutters 309, 318 swing, i. e., the common axis of shafts 340. At its opposite sides, frame 61 has a pair of downwardly extending arms 62 and 63 which at their lower ends are carried through split bearing collars 357 and 358, respectively, by flanged discs 359 welded to the tubular housings 325 in the main frame extensions 27 and 28 (see Fig. 10). Adjustment of the secondary frame 61 about its pivotal axis is provided by a pair of double acting piston motors 66 and 67 the cylinders of which are pivotally connected to brackets one of which is seen at 68 in Fig. 4 of the drawings, which brackets are supported from the opposite steps or operator's platforms 328 on the mining machine main frame 20. The upper ends of the pistons of the hydraulic motors 66 and 67 are pivotally attached to brackets 69 and 70 formed on opposite sides of the rear portion of the secondary frame 61.

Pivotedly mounted on the supplemental frame 61 and in fact forming a part thereof is a pivot plate 71 forming part of a turntable (see Fig. 2) which is journaled on a pivot ring 72; the plate 71 being swingable about the pivot ring 72 by a double acting hydraulic motor 73 which is preferably housed largely within the housing-like hollow structure of the secondary frame 61. The front end of pivot plate 71 rides and slides sidewardly pivotally upon an arcuate support or bearing bar 432 carried by the front of the top plate of frame 61 and the plate 71 is provided at its front end upon its top surface with a stop block 433. Slidable longitudinally in channel guides 74 formed on the plate 71 is a slide plate 75 which in turn is provided with channel guides 76 in which is slidably mounted a slide assembly 77. Slide plate 75 carries upon its bottom surface a stop block 434, which is adapted to abut stop block 433 of pivot plate 71 for limiting the forward movement of slide plate 75, and upon its top surface a front top stop block 435 and a rear stop block 436. Slide assembly 77 includes a bottom plate 360 and a similar but slightly smaller and thicker top plate 361 spaced apart at the rear of their side edges by slide blocks 362 which slide in side channel guides 76 of plate 75. A spacer block 80 spaces the front edges of plates 360 and 361 apart. A stop block 437 on the underside of plate 360 operates between stop blocks 436 and 435.

In operation, when the slide assembly 77 is moved to its outermost or forward position, stop block 434 engages stop block 433 to limit the forward movement of plate 75 and stop block 437 engages stop block 435 to limit the forward movement of slide assembly 77. When slide assembly 77 is moved rearwardly stop 437 engages stop 436 to retract plate 75.

Mounted upon the slide assembly 77 is a combination motor driven rotary drill and hydraulic coal breakdown device 78. The extension slide plate 75 and the extension slide assembly 77 provide for extended telescopic longitudinal sliding movement of the drill and hydraulic breakdown device 78 so as to feed it forwardly whereby it will bore into solid coal above the bottom kerf cutter to a position wherein its hydraulically expandible head portion 400 may be operated to break the said solid coal by expansion.

The longitudinal feeding movement of the combination rotary drill and hydraulic expandible coal breakdown device 78 is provided by a double

acting hydraulic feed motor or cylinder 78 which is pivotally attached at its rear end to the rear end of the plate 71 and at its forward end in the spacer block 80 at the forward central portion of the slide assembly 11. Because the secondary frame 61 is swingable about a horizontal axis and plate 71 which is carried by frame 61 is swingable about an upright axis it is obvious that the combination powered drill and hydraulic coal breakdown device 78 is swingable at various angles above the bottom kerf cutter bars 44 and 45 and thus the combination rotary drill and hydraulically expandible coal breakdown device 78 may be swung to position the drill and its hydraulically expandible head over an appreciable portion of the mine face which has been undercut by the cutter mechanisms 44, 45, etc.

The drill or mechanism 78 including its hydraulically expandible head mechanism is shown in Fig. 13 and the driving motor mechanism for said drill is shown in Fig. 14 of the drawings. The driving motor is "permissible," that is, it is of explosionproof construction and it includes a housing 363 which includes a central portion, a rear portion 364, and a front portion 365. The central portion of the motor housing includes a transverse partition 371 from the center of which there extends rearwardly a tubular shaft housing 366. The rear portion 364 of housing 363 includes a forwardly extending tubular shaft housing 367 which abuts and seals with the end of the housing 366. The rear end of housing 367 is bored to receive an anti-friction bearing 368 and the front portion 365 of the motor housing 363 is bored to receive an anti-friction bearing 369. Bearings 368 and 369 each includes a suitable seal for preventing the loss of lubricant from a gear chamber 370 formed by the transverse partition 371 and the front housing portion 365. Bearings 368 and 369 carry a shaft 372 which extends through the front portion 365 of the motor housing, the tubular shaft housing and through the rear wall of rear housing portion 364. Within the gear chamber 370 the shaft 372 carries a gear 373 which is spaced from the partition 371 through an anti-friction thrust bearing 374 carried by a boss formed on the forward end of tubular housing portion 366. Gear 373 is driven by a pair of armatures 375 and 376 of a pair of spaced electric motors contained within the motor housing 363. For the sake of simplicity only the motor armatures 375, 376 of the electric motors are shown. The motor armatures 375 and 376 are carried at their forward ends in anti-friction bearings received in cups 377 formed in the motor housing partition 371 and the rear ends of armature shafts 375 and 376 are carried by anti-friction bearings supported in the rear wall of rear motor housing portion 364. The armature supporting bearings in the rear housing portion 364 are secured to the rear ends of armature shafts 375 and 376 by nuts and are covered by plates attached to the rear end of the housing section. Suitable lubricant retainers are provided for preventing the leakage of lubricant past the armature supporting bearings into the motor chamber 378 of motor housing 363. The forward wall of front portion 365 of the motor housing 363 is provided with a pair of openings 379, one in front of each armature shaft 375 and 376, which are closed by covers 380. The armature shafts 375 and 376 at their forward ends and immediately behind the openings 379 carry pinion gears 381 and 382, respectively, which are secured to the armature shafts by keys 383.

and nuts 284. Shaft 372 is bored longitudinally at 385 and at 386 to form conduits for hydraulic fluid which fluid, as hereinafter described, operates the expansion mechanism of the head of the drill or boring tool 387 of the combination rotary drill and hydraulically expandible coal breakdown device 78. The rear end 388 of shaft 372, as previously described, extends through the rear wall of rear motor housing portion 364. End 388 of shaft 372 is grooved circumferentially at 389 and this groove connects directly with bore or conduit 385. The rear end 388 of shaft 372 is circumferentially grooved at each side of circumferential groove 389 to receive suitable hydraulic fluid sealing devices such as O-rings 390. Bore or conduit 386 extends through the rear end of shaft portion 388. Fitting closely over the rear end of shaft 372 is a cap or cover 391 having a central bore which closely surrounds the shaft portion 388 and which is secured to the rear wall of motor housing portion 364. A hydraulic fluid conduit 392 in the side wall of cap or cover 391 connects with the circumferential groove 389 for conducting hydraulic fluid to or from bore 385 in shaft 372 and a hydraulic fluid conduit 393 in the end wall of cap or cover 391 connects with the bore or conduit 386 of shaft 372. Motor armatures 375 and 376 are driven in the same direction to drive the gear 373 which in turn drives the shaft 372, the forward end of which is threaded to receive the drill or boring tool 387. The cap 391 co-operates with the rear end portion 388 of shaft 372 to provide a hydraulic fluid transfer device in which the hydraulic conduits 392 and 393 will remain in constant communication with their respective bores or conduits 385 and 386.

It will be seen that the spaced arrangement of the motor armature shafts which is here employed permits the construction of a relatively thin rectangular motor having a high power rating and the motor, because of its thinness, permits a drill or boring tool carried by its main shaft to be operated quite close to the ceiling of a mine room.

The drill or boring tool 387 includes a shaft or shank 395 having an internally threaded cup-like portion 394 at its rear end adapted to be threaded upon the forward end of motor shaft 372. Drill shank 395 includes longitudinal bores or hydraulic fluid conduits 385', 386' which connect with the conduits 385 and 386 in the motor shaft 372 and suitable sealing devices such as O-rings are provided in the rear end of cup-like portion 394 at 396 and 397. Wrapped about and welded to the drill shank 395 is a suitable flute or conveyer member 398, the function of which is to remove rearwardly cuttings or borings from a bore being formed by the tool to prevent jamming or binding of the drill in the bore. The front end of drill shank 395 is threaded at 399 to receive the hydraulically expandible head mechanism and cutter bit holder 400 of the drill or boring tool 387.

Portion 400 of the drill or boring tool 387 includes a flat forwardly extending cutter bit and pilot drill holder portion 401 which carries four staggered forwardly outwardly extending or fanned cutter bits 402 and a central pilot drill 403 which extends forwardly of the cutter bits 402. When boring tool 387 is rotated upon its longitudinal axis and fed to bore into solid coal the pilot drill 403 functions in a normal manner to drill or bore a lead opening of small diameter in the coal. Because the cutter bits 402 are fanned 75 in staggered relation the cutting edge of each of

them lies upon a different radius from the longitudinal axis of the boring tool 387 and pilot drill 403 and each cutter bit rotates to cut into the coal in a separate path. The path of the outermost cutting edge of the outermost cutter bit 402 determines the diameter of the bore which will be cut by the boring tool 387.

Rearwardly of the cutter bit and pilot drill holder 401 the expandable head and cutter bit holder 400 includes a cylinder 404 in which there is a cylindrical boss 405. A hollow piston 406 fits within cylinder 404 and over the boss 405 and its inner end is provided with a flange 407 that carries sealing mechanism 408 by which it is made fluid tight with the cylinder 404. The outer end of cylinder 404 is closed by a sealing ring 409 which surrounds the head of piston 406 and is threaded and locked to the body of head 400. It will be seen that the arrangement described provides a cylindrical chamber 410 between the sealing ring 409 and the flange 407 of piston 406. Hydraulic fluid is supplied to and exhausted from chamber 410 through the conduit 386' in the drill shank 395 and a conduit 411 in the head 400.

The inner end of cylindrical piston 406 is notched at 412 and the cylindrical boss 405 is grooved at 413 to permit the passage of hydraulic fluid under pressure from the area 414 behind the piston flange 407 to a chamber 415 behind the head of piston 406. Hydraulic fluid is supplied to and exhausted from the area 414 through a conduit 416 in the body of head 400 that connects with conduit 386' in drill shank 395. It will be seen that by this arrangement the area of the entire diameter of the piston is utilized to force the piston outwardly and yet substantially the entire outer cylindrical surface of boss 405 acts to guide the piston 406. As piston 406 moves outwardly under pressure of hydraulic fluid fed through conduits 386, 386' and 416, that fluid contained within the cylindrical chamber 410 must necessarily be displaced and such fluid is displaced through conduits 411, 386' and 386. Piston 406 is returned to its inner position by hydraulic fluid supplied to chamber 410. Head 400 is sealed to the threaded end 399 of drill shank 395 by suitable O-rings 417 which are retained in grooves therein and abut the end of drill shank 395. The expandable head and cutter bit holder is provided with a helical flute for conveying cuttings rearwardly when the boring tool is operating in a bore. This helical flute includes a thin front portion 418 adapted to collect cuttings immediately behind the cutter bits 402 and to convey them rearwardly to the rear portion 419 of the flute which discharges the cuttings to the rear of the head portion 400 and to the conveyer flute 398 of the drill shaft or shank 395. The front and rear portions 418 and 419 of the helical flute merge and the rear portion 419 is considerably thicker, as seen in Fig. 13, than the front flute portion 418 for the purpose of providing a large bearing area or abutment surface against the wall of the bore for preventing sideward movement of the boring tool 387 when piston 406 is operated to break down solid coal.

It will, of course, be seen that to break down solid coal the bore is first formed therein by the boring tool and that the rotation of it is stopped before hydraulic fluid under pressure is supplied to the area 414 and chamber 415 to force the piston 406 outwardly whereby its head will abut the wall of the bore opposite the wide rear flute portion 419 and that continued expansion or outward movement of the piston 406 will break or

burst the walls of the bore thus to fracture and break down the solid coal in which the mechanism is expanded.

Attention is now directed particularly to Figs. 1, 2, 9 and 10 of the drawings and to the construction of the receiving, discharge, or elevator conveyer 46. As seen, particularly in Figs. 2, 9 and 10 of the drawings, said receiving and discharge conveyer 46 is provided at its forward end, which is positioned largely above the aforescribed sloping top plate 22 of the main frame 20, with a bottom plate 81 which extends transversely between a pair of upright side plates 82 (see particularly Fig. 9), which side plates 82 are welded to said sloping top plate 22. Above the bottom plate 81 is a false bottom plate 83 likewise welded to the side plates 82, said false bottom plate 83 in fact forming the bottom of a receiving hopper 84 (see Fig. 9) adjacent the forward portion of said conveyer 46, said hopper 84 being additionally formed by sloping side plates 85 and upright side walls 86, all as best seen in Fig. 9 of the drawings.

As above indicated, the hopper 84 is formed rigidly with the main frame 20. Communicating with and extending rearwardly from the hopper 84 and in part forming a continuation thereof, is a two-section trough which is formed by a rear discharge trough forming boom 87 (see Fig. 1) and intermediate conveyer section 88, the section 88 being pivoted with respect to the main frame 20 about a transverse horizontal axis provided by a pair of spaced pivot pins, one of which is seen at 89 in Fig. 2 of the drawings. In addition, the conveyer boom 87 is pivoted about a vertical or upright axis with respect to the conveyer section 88 so that the boom 87 can swing about said upright axis.

The conveyer section 88 includes a bottom plate 90 which is a continuation of the bottom plate 81, and a false bottom plate 91 which is a continuation of the false bottom plate 83, the rear end of the bottom plate 90 being enlarged and generally cylindrical in shape to provide a swinging support for the boom 87 which is supported thereon by a pivotal connection 100 and by rollers, one of which is seen at 92 in Fig. 1 of the drawings.

Swinging movement of the boom 87 about its upright axis is provided by a pair of hydraulic piston motors 93 and 94 (see Figs. 1 and 15) which are on opposite sides of the boom and which co-operate with a cable 95 attached at opposite ends to opposite sides of said boom 87 and at its center to the enlargement of the bottom plate 90 of the conveyer section 88.

Pivotal movement of the boom 87 and the conveyer section 88 together about the horizontal axis provided by the pivots, one of which is seen at 89, is effected by the hydraulic piston motor 96 (see Figs. 1 and 15) attached at opposite ends to brackets on the enlargement of the bottom plate 90 and on the platform 42, respectively.

To convey the material received in the hopper 84 and discharge it over the rear head sprocket 97 of the boom 87, I provide an endless conveyer chain 98 provided with flights 99, the upper run of the chain 98 and the flights traveling successively over the false bottom plate 83 of the hopper 84, the false bottom plate 91 of the conveyer section 88, and a continuation thereof which is provided in boom 87 and forms the bottom plate therefor, the return run of said conveyer traveling between said false bottom plates and the bot-

tom plates 81 and 80, said conveyer chain 98 extending between the discharge sprocket 87 at the rear or discharge end of the boom 87 and a drive sprocket 101. Appropriate guiding and retaining means 102 are provided for the upper run of the conveyer chain 98 throughout the several sections of the discharge conveyer including the hopper thereof, said guide means being broken to provide the pivotal adjustments above described.

Attention is now directed to the several gear trains by which the various parts of the machine are driven from the electric motor 43. The armature shaft of said motor 43 extends longitudinally of the machine and is connected to a drive shaft 103 (see Fig. 1) which extends into the housing formed by the main frame 20, by extending through the rear wall 25 thereof where it is supported upon an anti-friction bearing 104, there being a flexible coupling 105 interposed between the armature shaft of motor 43 and the drive shaft 103. The front end of the drive shaft 103 is supported by an anti-friction bearing carried in a transversely extending plate 106, which plate is welded to the top plate 22 and to the main frame plates 21 of the main frame 20. The outermost end of said shaft 103 is provided with a bevelled pinion which drives a ring gear 107 which is attached as by screws to one portion of a friction clutch 108 which is the friction clutch for controlling the bottom kerf cutter chains 54, 55, the cutter chains of shear kerf cutters 309 and 310, and the chains of endless chain conveyers 265 and 266. Clutch 108 and the operating mechanism therefor, which operating mechanism is disclosed in detail in Fig. 5 of the drawings, will be described more completely hereinafter.

The ring gear 107 is connected to drive an upwardly extending sloping stub shaft 109 which is supported at its top and bottom in spaced journal bearings, the bottom journal bearing being carried by a casting 110 which is rigidly attached to the bottom plate 23 of the main frame (see particularly Fig. 8 of the drawings). The top anti-friction bearing which supports the stub shaft 109 is supported in a cup which is formed in a disc-like cap 111 which is received in a circular opening in the top plate 22. Stub shaft 109 is provided at its bottom with a bevel gear 112.

Attention is now directed particularly to Fig. 8 of the drawings which shows a portion of the drive for both the crawlers and the conveyer mechanism 98, 99. The bevel gear 112 meshes with a pair of reversely rotated bevel gears 113 and 114 which obviously rotate in reverse directions under the driving influence of said bevel gear 112. Gear 113 is keyed to the housing 115 of a friction type clutch which is journaled on anti-friction bearings 116, 117 carried by a transversely extending shaft 118. Keyed to the shaft 118 is a large gear 119 which is in that portion of the gear train which is individual to the crawler drives.

Actuation of the friction clutch 115, etc., is effected in a well-known manner by compressing the friction plates thereof. To this end a compression ring 120 is provided within the housing 115 which when moved to the right, as viewed in Fig. 8, will cause application of the clutch. The ring 120 is actuated by the actuating bar 121 extending transversely through a slot in the shaft 118, said bar being urged to the left as viewed in Fig. 8 by a compression spring 122 which is re-

ceived in the bottom of a longitudinal bore 123 formed in the left-hand end of said shaft 118.

Actuation of the bar 121 is effected by a rod or shaft 124 which is provided with a ball type head 125 which preferably extends to the left beyond the extremity of the shaft 118. Engaging the ball head 125 is the reduced head of a hydraulic piston 126 contained within a hydraulic cylinder 127 which is removably attached to a bracket 128 which itself is removably attached to the left-hand main plate 21 adjacent an opening therein which provides for removal of the gear 119. It is obvious that by applying hydraulic pressure to the cylinder 127, the piston 126 will actuate the rod 124 to apply the clutch 115, etc. It may be stated that this is the clutch which provides for the reverse travel of the mining machine.

The aforescribed bevel gear 114 is keyed to a clutch housing 129 of a clutch which is similar to that just described, except for a difference which will hereinafter be pointed out, and this clutch is the clutch for driving the machine forward. The operating mechanism for said clutch having housing 129 is by means the same in construction as that just described, and consequently the same reference characters are employed in designating these parts; except for purposes of identification the hydraulic cylinder is designated 130.

There is one difference between the clutch having housing 129 and that having housing 115, in that the former constitutes part of a direct drive from the bevel gear 112 to the conveyer chain 98. To effect this drive the right hand end of the housing 129 has keyed to it a drive sprocket 131 having a large hub. There is a smaller sprocket 132 on this large hub which drives an oil pump through a chain, which pump is for the purpose of maintaining a predetermined oil level in the sump formed in the bottom of the housing formed by the main frame 20. Whenever the liquid level reaches a certain height, this pump automatically elevates it to the reservoir, not shown.

The sprocket 131 drives a sprocket 133 (see Fig. 11) through a chain 134 (see Fig. 2). Before proceeding with this description, it may well be noted at this time that so long as the motor 43 is driven in a single direction, the sprockets 131 and 133 will always travel in the same direction since they are directly connected thereto. On the other hand, the shaft 118 and the gear 119 which is keyed thereto may be driven in reverse directions by the selective operation of the clutches 115, etc. and 129, etc., under the control of the hydraulic piston motors 127, etc. and 130, etc., respectively. It may additionally be pointed out that the drive shaft 118 is supported at its opposite ends in anti-friction bearings 135 and 136 which are received in cups formed in the brackets 128 connected to the side members 21.

Proceeding now with the description of the drive for the conveyer chain 98 and referring particularly to Fig. 11 of the drawings, it is seen that the sprocket 133 is formed as an integral part of the housing of a friction clutch 137 which is mounted on anti-friction bearings and is adapted to control the driving of a shaft 138 mounted at its opposite ends in anti-friction bearings 139, 140, the former being supported by the left-hand main plate 21, and the latter being supported in a cup formed in the previously mentioned bracket 38.

Actuation of the clutch 137 is by mechanism quite similar to that above described for actuating the clutches 115, etc. and 129, etc., and there-

fore will not be specifically described again except to point out that the hydraulic piston motor 141 actuates the mechanism which ultimately applies the friction plates of said clutch 137. When said clutch 137 is applied, the shaft 138 will be driven and always in the same direction so as to operate the conveyer mechanism 98, 99 to convey the material from the hopper rearwardly and discharge it over the rear sprocket of the boom 87.

Mounted on the shaft 138 and keyed thereto is the previously described drive sprocket 101 which drives said conveyer chain 98. It may be mentioned that this sprocket 101 is within a sub-housing which is open at its bottom, as clearly disclosed in Figs. 2 and 11 of the drawings, and since the major portion of the housing provided by the main frame 20 is oil-tight, I provide oil seals 143 adjacent opposite ends of the elongated hub of sprocket 101 and where the shaft 138 extends through upright partitions 144 forming inner walls of the housing constituting the main frame 20.

Attention is now directed particularly to Figs. 2, 9 and 10 and to the gear train for driving the afore-described kerf cutting and gathering chains 54 and 55 and the chains of conveyers 265 and 266. Formed integral with the housing of the afore-mentioned clutch 108 is a gear 145 (see Fig. 2) and actuation of the clutch 108 will effect the driving connection between the shaft 109 and said gear 145. Said gear 145 meshes with and drives a large gear 146 seen only in part in Fig. 2 of the drawings and illustrated in section in Fig. 9 of the drawings, to which attention is now particularly directed. The gear 146 is attached to the lower end of an upwardly sloping shaft 147 which is supported on spaced anti-friction bearings 148 and 149, the former being carried in a removable cup forming plate 150 mounted on a sloping plate 151 which plate 151 is welded at its ends to the main frame plates 21 (see particularly Fig. 9). Keyed to the top of the shaft 147 and between the plates 22 and 151 is a gear 152 which meshes with an idler gear 153 having an integrally formed shaft mounted upon spaced anti-friction bearings 154 and 155 carried by the plate 22 and a cup formed in the plate 150, respectively.

As best seen by reference to Fig. 10 of the drawings, the gear 152 meshes with a gear 156 and the gear 153 meshes with a gear 157, the former being mounted upon an upwardly sloping shaft 158 and the latter on a similar shaft 159. Shaft 158 is mounted in spaced bearings 160 and 161, the former being carried in a cup mounted on plate 151, and the latter in a cup formed in a cap of an inward cup extension 162 formed as an integral part of the main frame in that it is welded to the left-hand main plate 21 and to the afore-described left-hand side plate 82. Within the cup extension 162 the shaft 158 carries a bevel gear which is similar to the bevel gear 346 on upright shaft 159 and at its upper end the shaft 158 is provided with a double sprocket 163 which is similar to sprocket 164—308, previously described, which drives the cutting and conveying chain 55 and the chain of conveyer 266.

The shaft 159 is mounted in spaced bearings of structure duplicating that just described for the shaft 158. It is obvious from the gearing arrangement disclosed in Figs. 9 and 10 of the drawings that the shafts 158 and 159 will be driven in opposite directions. It may be stated

that this direction is not reversible without reversing the direction of rotation of the motor 43 which is essentially a non-reversible motor. Furthermore the direction of travel of the chains 54 and 55 is such that the inner runs adjacent the trough 49 always move from the front to the rear. Thus cutting of the coal is equalized on the two sides of the composite cutter bar 44, 45, and the coal is conveyed rearwardly thereby and discharged into the receiving hopper 84 of the discharge conveyer 46. It is thus obvious that the function of the clutch 108 is to apply and release the driving connection to drive shafts 158 and 159 of the combination cutting and conveying chains 54 and 55 and the chains of conveyers 265 and 266.

As previously set forth, bevel gear 346 on shaft 159 meshes with and drives bevel gear 343 of shaft 340 and shaft 340 is connected through a manually operated clutch 350 to drive sprocket 348 which in turn drives cutter chain 316 of upright side kerf cutter bar 310. The mechanism that drives the kerf cutter chain of upright cutter bar 309 is a duplicate of that described in connection with cutter bar 310. Therefore it will be seen that its drive shaft will be driven from shaft 158 in such direction as to drive the chain of cutter bar 309 in a clockwise direction, as seen in Fig. 4, while the drive shaft 340 of cutter bar 310 will be driven in such direction that the chain 316 will be driven in a counter-clockwise direction, as seen in Fig. 3. It is obvious that by means of the manual clutches 350 the cutter chain of either cutter bar 309 or 310 may be disconnected from its driving shaft independently of the other.

Attention is now directed particularly to Figs. 2 and 5 of the drawings and to the mechanism for operating the clutch 108. Extending through the housing of clutch 108 is a plurality of operating pins 165 (see Fig. 2), which contact a compression ring within the housing and an operating ring outside the housing which is mounted upon an anti-friction bearing 166 carried upon a shiftable ring 167 which is shiftable along the axis of the shaft 109. The ring 167 is held against rotation by a projection 168 which extends into a slot formed in the periphery thereof, the projection 168 being rigidly attached to the casting 110.

Axial clutch applying movement of the ring 167 is provided by four small hydraulic piston motors, the pistons of which are substantially equally spaced about the lower face of the ring 167, two of said piston motors being seen at 169 in Fig. 5 of the drawings. In the interest of simplicity, these four motors are illustrated as a single motor in Fig. 15 of the drawings. The head ends of all of the four piston motors 169 are connected in parallel, the connection of two of them being illustrated by means of the pipe 170 in Fig. 5 of the drawings. It is obvious that since the head ends of all four pistons are connected in parallel, hydraulic fluid delivered to one of them 65 will be distributed to all of them.

It is to be noted that the normal tendency is for the clutch to become disengaged under the action of gravity since the actuating mechanism is all below the clutch discs rather than above it, 70 and experience has demonstrated that this makes for much smoother clutching action than where a reverse condition is produced, particularly where a relatively large clutch is involved as is the clutch 108. It is, of course, obvious that 75 when hydraulic fluid is supplied to the four hy-

21

draulic piston motors 168, their pistons will move upwardly together to push upwardly on the ring 167 and thus engage the clutch 168. When the hydraulic fluid is released from the motors 168, the clutch 168 will release.

Attention is now directed particularly to Figs. 2, 6, 7 and 8 of the drawings and to that branch of the gear train by which the crawlers 31 and 32 are driven from the motor 43. As previously described in connection with Fig. 7 of the drawings, the gear 119 may be driven in reverse directions under the selective operation of the clutches 115 etc., and 128 etc. Said gear 119 meshes with and drives a gear 171 (see Fig. 7) which is keyed to a hub 172 loosely journaled on a transversely extending shaft 173 mounted in spaced anti-friction bearings 174 and 175 carried in the left-hand main frame plate 21 and an upstanding supporting plate 176, respectively, the latter being within the main frame housing 20. The hub 172 is provided with an integral pinion gear 177 which meshes with and drives a large gear 178 of a slow or feeding speed gear reduction mechanism, the gear 178 being loosely journaled on a shaft 179 mounted in anti-friction bearings 180 and 181 mounted in main frame plate 21 and a cup formed in an interior upstanding plate 182 welded to the main frame 20.

The outer end of the hub 172 is provided with teeth of a jaw clutch, the shiftable clutch member 183 of which is feathered on the shaft 179. The hub of the gear 178 is provided at its right-hand side with clutch jaws forming part of a jaw clutch, the shiftable clutch member 184 of which is feathered on the shaft 179.

Operating mechanism 185 is provided for the shiftable clutch members 183 and 184 so that said clutch members may both be in disengaging position but both of them cannot be in clutch engaging position at the same time, and by operating the hand lever 186 said shiftable clutch members 183 and 184 may be thrown to provide for the selective high tramping speed or low sumping or feeding speed drive of the combination mining and loading machine. It may be mentioned at this time that practically all of the control levers of the mining machine are duplicated on opposite sides of the machine and to this end they are interconnected by cross-rods, the cross-rod for the two levers 186 on opposite sides of the machine being seen at 187 in Fig. 6 of the drawings.

The right-hand end of the shaft 173 has keyed thereto a pair of spaced pinions 188 and 189 between which is a large gear 190. Gear 190 is driven by a pinion 191 formed integral with the shaft 179. It is obvious that when shiftable clutch member 183 is in engagement, there will be a direct drive from the gear 171 to the two gears 188, 189, and this is the high speed or tramping drive. On the other hand, when shiftable clutch member 184 is in engagement, at which time clutch member 183 is necessarily disengaged, there will be a low or feeding speed drive to the crawlers by the gear reduction provided by gears 177, 178, 191 and 190.

It may also be mentioned that in Fig. 7 I have illustrated at 192 a filter for filtering the hydraulic fluid, which is provided with mechanically operated wiping mechanism 193. It may also be mentioned that the dual control levers, some of which are shown in Fig. 7, control various devices on the machine. For example, the dual levers 194 control the clutch 168, the dual levers 195 control the clutch 137, and the dual levers 75

22

166 control a hydraulic valve which operates the hydraulic piston motor 96 for raising and lowering the boom 67.

Attention is now directed particularly to Fig. 6 of the drawings. The aforescribed pinions 188 and 189 mesh with and drive large gears 197 and 198, the former of which is individual to the drive of the traction device 31, and the latter of which is individual to the drive of the traction device 32. Since these two drives are substantially duplicated, a description of one will suffice for both. Gear 197 drives a transverse shaft 199 which is mounted in spaced anti-friction bearings 200 and 201, the former being mounted in a bracket 202 carried by the left-hand main plate 21, the latter being mounted in a cup in upright plate 182.

Mounted upon the shaft 199 is a clutch 203 which is actuated by a hydraulic piston motor 204, the construction of the actuating mechanism being substantially the same as that heretofore described in detail in connection with the clutches illustrated in Fig. 8 of the drawings, namely, 115 etc. and 128, etc., and consequently it is deemed unnecessary to repeat a description of this clutch operating mechanism.

Keyed to the housing 205 of said clutch 203 is a gear 206 which meshes with and drives a larger gear 207 mounted on a shaft 208 supported in spaced anti-friction bearings 209 and 210, the former being mounted in a cup formed on the left-hand main plate 21, the latter in a cup formed on upright plate 182. At its left-hand end the shaft 208 carries a drive sprocket 211 which meshes with and drives the chain of the traction device 32. It is obvious that by operating the hydraulic motor 204, the clutch 203 may be selectively engaged or disengaged, and when engaged will effect a driving connection between the shaft 199 and the gear 206.

The central portion of the housing 205 of the clutch 203 also acts as a brake drum, and co-operating therewith is hydraulic braking mechanism 212 which is pivotally supported in part by bracket 213 carried at the upper end of the left-hand side plate 21.

It may be stated that the traction device 31 is driven from the gear 198 through a clutch 214 and reduction gearing which ultimately drives a sprocket 215, this drive gearing being a duplication of that just described between gear 197 and sprocket 211. Hydraulic brake mechanism 216 is provided in association with the housing of clutch 214 similar to the brake mechanism 212. The clutch 214 is also provided with a hydraulic motor 217 to control its engagement and disengagement.

At the left-hand side of Fig. 6 of the drawings there is illustrated at 218 a filter which is in the suction line of the hydraulic system and consequently is a low pressure filter. The previously described filter 192 illustrated in Fig. 7 is a high pressure filter, that is, it is in a high pressure line.

Referring also to Figs. 1 and 6 of the drawings it will be seen that the shaft 103 (see Fig. 1) carries a double sprocket 219, and this double sprocket drives a pair of chains 220 and 221 which drive a pair of pumps 222 and 223, the former only being seen in Fig. 6 of the drawings, but both of the pumps are illustrated in the piping diagram of Fig. 15 of the drawings. These two pumps 222 and 223 provide hydraulic fluid pressure for operating the various mechanisms and separate pumps are preferably provided for

reasons hereinafter described in connection with the hydraulic system.

Attention is now directed particularly to Fig. 15 of the drawings wherein the hydraulic system is illustrated. As here illustrated the hydraulic system includes a tank 224 which in fact may be formed by the bottom of the housing formed by the main frame 20. Leading from the tank 224 is a feed pipe 225 by which oil is delivered to the pump 222, there being a similar feed pipe 226 leading to the pump 223. Leading from pump 222 is a high pressure line, pipe or conduit 227, a similar high pressure line, pipe or conduit 228 leading from pump 223. Pressure gauges 229 and 230 are associated with the lines 227 and 228, respectively. The pipe or conduit 227 leads to a high pressure relief valve 231 which, of course, is normally closed and thus normally directs the fluid to the continuing high pressure conduit 227, but when actuated provides a by-pass to the return pipe 232. A similar high pressure relief valve 233 is provided in the high pressure line 228 and also provides a by-pass under excessive pressure leading to the return line 232. High pressure line 227 delivers hydraulic fluid to a hydraulic accumulator 234, the output of which is delivered by pipe or conduit 235 to a plurality of individual control valves. In addition, the high pressure pipe 227 has a lower branch which leads to a six-unit hydraulic control valve 236 where there are six individually operable valves each controlling individual hydraulic mechanism as hereinafter described. That is, the six-unit valve 236 has one set of dual levers which control the hydraulic piston motor 96 by way of pipe or conduit 237 to raise and lower the boom 87. A second valve thereof provided with dual levers controls the parallel double acting hydraulic piston motors 66 and 67 for raising and lowering the supplementary mining mechanism 60 by way of conduits 238 and 239. Since these hydraulic piston motors 66 and 67 are double acting, the supplementary mining mechanism 60 may be raised or lowered under power, and it may be stated that the construction of each of the valves of the six-unit hydraulic valve mechanism 236 is such as to lock any hydraulic motor in position when the valve is in its neutral or normal position. A third valve of the unit 236 controls the double-acting hydraulic piston motor 58 by way of conduits 240 and 241 which provides for the raising and lowering of the front end of the cutter bars 44 and 45. A fourth valve of this unit 236 provides for the simultaneous operation of the single acting hydraulic piston motors 93 and 94 for swinging the boom 87, this control being by way of conduits 242 and 243, respectively.

The fifth and sixth valves of six-unit valve unit 236 control the operation of piston motors 337 and 337', respectively, which swing the upright side kerf cutter bars 309 and 310 about a horizontal axis, piston motor 337 being connected to valve unit 236 through conduits 422 and 423 and piston motor 337' being connected to valve unit 236 through conduits 424 and 425.

The high pressure line 228 leading from the pump 223 feeds a three-unit hydraulic control valve 244, and one of the valves of this unit controls the hydraulic piston motor 73 by way of conduits 245 and 246, thus controlling the swinging of the turntable plate 71 of the supplemental mining mechanism 60. A second valve of this unit 244 controls the feed cylinder or motor 79 by way of conduits 247 and 248, thus controlling the rectilinear feeding of the combination drill

and hydraulic coal breakdown device 78. It is obvious that both the piston motors 73 and 79 are double acting and that motor 73 provides for reverse swinging movement of the drill and breakdown device 78 about an upright axis while motor 79 provides for reverse rectilinear feeding movement thereof under power.

It is to be noted that the three-valve unit 244 is supplied from pump 223 while the six-valve unit 236 is supplied from the pump 223. This is desirable particularly in view of the fact that it is generally desired to swing the supplemental mining mechanism 60 by the motor 73 at the same time that it is being swung to raise or lower it by the piston motors 66 and 67, and since these operations are under the control of hydraulic fluid from separate pumps, they can be carried on simultaneously without any interference whatever, thus reducing to a minimum the time for adjusting the position in which the combination drill and hydraulic coal breakdown device 78 is to operate.

It is also to be noted that there is no accumulator in the lines of either of these swinging mechanisms, as a consequence of which there will be a very quick and direct response to actuation of their control valves.

The third valve of three-valve unit 244 controls the hydraulic coal breakdown head 400 of drill 387 by way of conduit 420 which connects through transfer device 391 carried by drill motor housing 363 with conduit 385 in the motor shaft 372. A conduit 421 connects conduit 386 in motor shaft 372 with said third valve.

Returning now to a consideration of the mechanism operated by the fluid which passes from the accumulator 234 into the conduit or pipe 235, it is to be noted that this conduit 235 supplies hydraulic fluid to an individual valve 249 which controls the hydraulic motor 127 controlling reverse clutch 115 by way of conduit 250, and controls the forward clutch operating motor 130 which controls forward clutch 129 by way of conduit 251. The valve 249 is so formed that it is impossible for both of the clutches 115 and 129 to be simultaneously actuated, but by operating it in one direction, one of them will be actuated, and by operating in the other direction, the other will be actuated. These hydraulic motors 127 and 130 are single acting and thus a return conduit 252 is provided for the return flow of the hydraulic fluid from the valve 249 to the tank 224. A second individual valve fed by conduit 235 is seen at 253, and individual conduits 254 and 255 lead therefrom to hydraulic piston motors 204 and 217, respectively, for actuating the crawler control clutches 203 and 214, respectively.

It may be stated that the valve arrangement of these is such that motors 204 and 217 are normally actuated so that normally both clutches 203 and 214 are engaged to effect a driving connection to each of the crawlers, but actuation of valve 253 is such that clutches 203 and 214 may be selectively disengaged, and there is a mechanical interlock between this valve and the herein-after described valves for controlling the brake mechanisms 212 and 216 so that when clutch 203 is disengaged its brake 212 is applied, and similarly when clutch 214 is disengaged its brake 216 is applied.

A third individual control valve supplied from conduit 235 is seen at 256, and it controls the hydraulic brake mechanisms 212 and 216 by way of conduits 257 and 258, respectively. These brakes are normally disengaged.

The high pressure conduit 235 also provides a double reducing and high pressure relief valve 159 which provides hydraulic fluid at reduced pressure to pressure conduits 260 and 261 by way of valves 262 and 263, respectively, which conduits lead to hydraulic motors 169 and 141, respectively, the former controlling the clutch 108 which controls the operation of the cutting and gathering chains, and the other of which controls the clutch 137 for operating the discharge conveyor chain 98. Reduced pressure is desired for operating these clutches since it is desired that they slip in case any serious obstruction is encountered and also since it is desired that they be engaged somewhat gradually.

In view of the above description the mode of operation of the mechanisms of the machine will be clear. For example, the driving motor 43 will supply power for operating all of the power-operated devices contained in the machine and for driving all of the driven mechanisms except the combination power driven rotary drill and hydraulic breakdown device 78 which is driven by motor armatures 375 and 376. This includes the operation of the entire hydraulic system through the two pumps 222 and 223, the propelling of the crawler mechanisms 31 and 32 at high transportation speed or at a low sumping or feeding speed, the operation of the kerf cutting and gathering chains 54 and the conveyers 265 and 266 as well as the discharge conveyor chain 98.

It is to be noted that the various gear trains which connect the driving motor 43 with the final drive sprockets 163, 164-308 of kerf cutter and conveyor chains 54 and 55 and the endless conveyor chains of supplemental conveyors 265 and 266, the final drive sprockets 348 of the endless kerf cutter chain means 318 of the upright or shear kerf cutter bars 309 and 310 and the final drive sprocket 101 of the endless elevator conveyor chain 98 which operates in rear discharge boom 87, as well as the final drive sprockets 211 and 215 for the chains of the crawlers 31 and 32, are all permanently mounted relative to the main frame 20 of the mining machine.

It is also to be particularly noted that the shafts 158 and 159 which are the final drive shafts for and which carry the sprockets 163, 164-308 are mounted for rotation about fixed upright axes relative to the fixed sloping bottom plate 47 of main frame 20 which forms the bottom of the rear portion of conveyor way or trough 49 while the forward portions of the cutter bars 44 and 45 and supplemental conveyors 265 and 266 which carry the chains driven by the sprockets 163, 164-308 are swingable, under control of the operator, about the horizontal axis 264 by hydraulic piston motor 58.

The arrangements of the various gear trains and the shafts 158 and 159 relative to the main frame 20 above pointed out are particularly advantageous in one aspect in that they permit of a less complicated construction in which much complicated gearing and connections such, for example, as universal joints, shafts, gear boxes and the like are dispensed with. In another aspect these arrangements yield a construction wherein the gear trains are compact and more direct and in still another aspect the arrangements yield a machine which is less costly to manufacture and maintain.

After the machine is placed in a mine it can be operated at a high speed to bring it up to the mine face, and during this maneuvering

swinging of the boom 87 may be effected by the hydraulic piston motors 93 and 94 to move the machine through narrow entries, around mine posts, and along curved paths. The operation of the crawlers provides for both forward and reverse movements as well as swinging movement by the individual operation of any crawler while the other is disengaged and its brake mechanism applied. It is obvious that for reasons of safety the clutches 137 and 108 will be disengaged to disconnect all of the kerf cutter and conveyor chains of the machine from the driving motor 43 when the machine is not performing a mining operation.

15 The machine is highly flexible in operation and therefore capable of different methods of operation for mining and loading coal, some of which methods will now be described.

In one method of operation the machine is brought to a mine face where it is to operate, the upright or shear kerf cutter bars 309 and 310 are lowered to their lowermost positions which positions are determined by the hydraulic piston motors 337 and 337' and are such that the upright orbits of cutter bits of the kerf cutter chain elements on kerf cutter bars 309 and 310 may be not quite and no more than just tangent to the horizontal orbits of the uppermost of the fanned out cutter bits of bottom kerf cutter chain elements 54 and 55, this to prevent interference of the cutter bits of said upright and horizontal cutter chains with each other. With the clutch 108 disengaged the operator engages clutches 350 to connect the drive sprockets 348 of the endless upright or shear kerf cutter bars 309 and 310 to shafts 340. Clutch 108 is now engaged to cause the motor 43 to drive the kerf cutter and conveyor chains 54 and 55 of the cutter bars 44 and 45, respectively, the endless conveyor chains of the supplemental conveyors 265 and 266 and the endless kerf cutter chain elements of the cutter bars 309 and 310. Clutch 137 is also engaged to cause motor 43 to drive conveyor chain 98 of elevator or discharge conveyor 46. With all of these endless chains in operation and with the combination rotary drill and hydraulic coal breakdown device in its rearward position, as seen in Fig. 4, the machine is fed forwardly at its slow or sumping speed to the face of the solid coal to effect a first cutting or sumping operation. As the machine is fed forwardly the endless kerf cutter chains 54 and 55 of the bottom kerf cutter elements cut a deep horizontal bottom kerf, indicated at 427 in Fig. 4, in the solid coal and the endless kerf cutter chains of the upright or spaced side shear kerf cutter bars 309 and 310 cut two deep upright laterally spaced shear kerfs, indicated at 428. The machine is fed forwardly rectilinearly to embed the kerf cutters deeply in the coal and it may be fed forwardly to such position that substantially all of the horizontal portions of the cutter bars 44 and 45 are within the cut bottom kerf 427, as shown in Fig. 4.

65 Superficially it would appear that because the orbits of the kerf cutter bits of chains 54 and 55 of bottom kerf cutter bars 44 and 45 do not overlap and because the cutter bits of the kerf cutter chains of shear kerf cutter arms 309 and 310 70 may be operating in upright orbits which are not quite tangent to the horizontal kerfs cut by cutter chains 54 and 55, that there will be left in the solid coal into which the kerf cutters are cutting thin webs or ribs of coal one of which 75 would enter the bottomless conveyor way or

trough 49 between cutter and conveyer chains 54 and 55 and horizontal webs or ribs which would extend between the bottoms of the spaced upright side kerfs 428 and the bottom kerf 427. However, experience has taught that because of the more or less friable nature of coal and because of vibrations of the machine during the sumping operation these webs or ribs do not form.

After the machine has been sumped as described and with all of its kerf cutter chains in operation the hydraulic motors 337 and 337' are operated to move or swing the side kerf cutter bars 309 and 310 upwardly to a position wherein their outer ends will cut to the level or plane of the mine room ceiling.

It will be seen as shown in phantom lines in connection with the cutter arm 310 in Fig. 4 that when the arms 309 and 310 are elevated or swung to their desired upper limits upright kerfs 429 will be cut thereby and these kerfs 429 will include the bottom upright kerfs or sump cuts 428 and will have upper or top surfaces 430 that lie in a plane sloping downwardly rearwardly. It is desirable that the top surfaces of the finally cut upright kerfs should be substantially horizontal as indicated by the line or plane 431 in order that the coal above the surfaces 430 and below the line or plane 431 may be more readily removed and to leave a smooth mine room ceiling. In order to finish the kerfs to line or plane 431 after the arms 309 and 310 have been swung upwardly to the desired elevation the machine with the arms 309 and 310 elevated is backed rectilinearly out of the coal face whereby the shear kerf cutter chains will finish cutting the spaced upright kerfs. During the sumping operation and while the shear kerf cutter arms 309 and 310 are being swung upwardly to cut kerfs 429 the cuttings removed by the upper forwardly moving runs of the cutter chains of arms 309 and 310 are conveyed forwardly and spilled or discharged over the fronts of the arms whereupon the cuttings fall through the upright kerfs into the bottom kerf 427 where they are collected and conveyed by the conveyer and kerf cutter chains 54 and 55 into the conveyer way or trough 49 from which they are discharged in a manner more fully described hereinafter.

The combination rotary drill and hydraulic coal breakdown mechanism 78 may be used to break down coal above the bottom kerf cutter bars 44 and 45 and between the spaced upright shear cutter arms 309 and 310 while the machine is being sumped by swinging the mechanism 78 to such position that its drilling head 400 may be caused to enter the coal face above the bottom kerf cutter bars 44 and 45 at any lateral position between the shear kerf cutter arms 309 and 310 to form a bore in the coal above a cut portion of the bottom kerf 427 and between cut portions of the spaced upright or shear kerfs 428 which receives the entire head 400 of drill 387. With the entire head 400 in the bore its piston 406 may be operated to break down, shatter or burst by expansion the solid coal in which it is embedded. It will be seen with reference to Fig. 4 that the bottom kerf 427 has a height greater than the thickness of the kerf cutter bars 44 and 45 which will allow the coal above the bottom kerf 427 to expand downwardly when piston 406 is operated. Because the sumping speed of the machine is slow and the operation of the combination drill and hydraulic coal breakdown device 78 is fast relative thereto the breakdown operation may be repeated several times with the drill 387 swung

to different lateral positions while the machine is being sumped into the solid coal. The coal broken down in this operation, of course, falls upon the cutter and conveyer bars or arms 44 and 45 and for the most part the loose coal is collected and conveyed rearwardly along the conveyer way or trough 49 by the kerf cutter and conveyer chains 54 and 55.

When the sumping and coal breaking operation above described is completed, the forward motion of the machine is stopped and as the hydraulic motors 337 and 337' are operated to raise or swing the kerf cutter arms 309 and 310 upwardly the combination drill and hydraulic coal breakdown mechanism 78 may be elevated to successively different levels or horizontal planes and operated as described to break down the coal between cut portions of the side, upright, or shear kerfs 429 cut by kerf cutter arms 309 and 310 as the arms move upwardly to cut said kerfs.

The combination drill and hydraulic coal breakdown mechanism 78 may also be used to break down solid coal above the bottom kerf 427 and between the spaced upright or side shear kerfs 429 after the said kerfs have been completely cut. In carrying out this method of operation the mining machine is backed away from the mine face to finish cutting the upright kerfs 429 to the plane 431, as previously described, and the machine, preferably with its kerf cutter arms 309 and 310 in their lowered positions, is driven forwardly to cause the kerf cutter arms 309, 310, 44 and 45 to enter the kerfs which they have previously cut. The clutches 350 of side kerf cutter arms 309 and 310 may be disengaged to stop the operation of the upright kerf cutter chains if desired and the combination drill and breakdown mechanism 78 is then brought into operation to break down the mass of solid coal that is hanging from the mine room ceiling above the bottom kerf cutter 427 and between the spaced upright shear kerfs 429. It will be obvious that the breakdown mechanism 78 may be adjusted to bore into the coal in any number of desired positions to effect the complete breakdown of all of the solid coal hanging from the mine room ceiling. The number of positions in which the breakdown mechanism 78 will be operated to break down the coal will, to a large extent, depend upon the particular characteristics of the coal being mined, but in any event the breakdown mechanism 78 will be used in a manner so as to break the coal into lumps the largest size range of which may be handled by the conveyers of the mining machine.

The coal which is broken down by the breakdown mechanism 78 falls upon the tops of the bottom kerf cutter bars 44 and 45 and that coal which is above the conveyer way or trough 49 is first conveyed rearwardly in the trough by the co-operating portions of the kerf cutter and conveyer chains 54 and 55. As the coal being conveyed rearwardly along the way 49 reaches the upwardly rearwardly inclined portion of the bottom kerf cutter mechanism, the flights of the endless chains of conveyers 265 and 266 engage the coal and assist the chains 54 and 55 in conveying the coal up the inclined portion of the conveyer way or trough 49 from which the coal is discharged or spilled into the receiving hopper 84 and onto the rearwardly moving upper run of chain 98, said chain 98 conveying the coal received thereby rearwardly and discharging it from the rear end of the discharge boom 87 into a mine car,

buggy or the like. It will be seen that coal which has been broken down by the breakdown mechanism 78 will tend to accumulate as a pyramid upon the top surface of each of the bottom kerf cutter bars 44 and 45. This loose coal will be removed from the bottom kerf cutter bars as the machine advances into the mine face while cutting a successive kerf, the face of the mine into which the machine is being sumped causing the accumulated coal to be held against forward movement while the cutter bars 44 and 45 slide forwardly underneath it. As the cutter bars 44 and 45 advance under the loose coal, the flights of the chains of conveyers 265 and 266 which are mounted upon the rear inclined portions of the cutter bars 44 and 45 sweep the coal to the center of the machine where the coal is caused to enter the deepened conveyer way or trough 49 and is conveyed rearwardly up the inclined rear portion of the conveyer way 49 from which it is discharged or spilled into the hopper 84 and conveyed from the machine in the manner described. It is to be noted that the flights of the chains of conveyers 265 and 266 operate in overlapping staggered relation as they pass rearwardly through the way 49. This for the purpose of positively engaging the coal being moved rearwardly in the way 49 for assisting the chains 54 and 55 in conveying the coal up the inclined portion of the way, increasing the capacity of the way and for preventing loose coal from rolling or flowing downwardly over the cutter and conveyer chains 54 and 55.

The sumping operations above described are all first cutting operations, that is, they each describe the operation of the machine in making a first cut into a mine room face. The machine may be used to cut a tunnel if desired by repeating the sumping operations or by continuous forward operation of the machine. However, in the event the machine is to be used for tunneling, the covers 356 at the rear of shear kerf cutter arms 309 and 310 must be removed in order that all of the non-kerf cutting parts of the machine will lie between the kerf cutter arms 309 and 310 so that the body of the machine may follow through the tunnel. It will be seen, of course, that when the machine is used in a tunneling mining operation the cutter bars 309, 310, the breakdown mechanism 78, and the bottom kerf cutter and conveyer chains 54 and 55, may be operated continuously and that the forward movement of the machine in the tunnel causes the bottom kerf cutter bars 44 and 45 to move forward under the coal as it is broken down by the breakdown mechanism 78 and held against forward movement by the solid coal in advance of it while the kerf cutter and conveyer chains 54 and 55 and the supplemental conveyers 265 and 266 convey the coal from above the bottom kerf cutter bars 44 and 45.

The machine may also be used for increasing the size of the mine room by operating it to make a plurality of adjacent entries or cuts into the mine face and to break down the coal during each operation. In such operation the mining machine is sumped into the face of the mine room to make a first or entry cut, as previously described. The machine is then caused to make a second cut adjacent the entry or first cut. In making the said second cut it is not necessary to operate both of the upright kerf cutter bars 309 and 310 since the coal to be removed, assuming the second cut is being made to the right of the entry cut, will be defined at its left side by the right side wall of the previously cut entry,

therefore in sumping the machine for the second or next successive removal of coal from the mine face only the bottom kerf cutter chains 54 and 55 and the cutter chain of kerf cutter bar 309 will be operated. When the sumping or side kerf cutting operations are completed the breakdown mechanism 78 will again be used to break down the coal above the bottom kerf cutter element and to one side of the single upright kerf cut by the kerf cutter bar 309. Preferably cutter bar 310 will be in its lowered position to form an upright wall or dam extending upwardly above the outside of bottom kerf cutter bar 44 against which broken down coal may pile up rather than roll or fall over the side of the cutter bar. The second or successive cut may be repeated any number of times until coal has been removed from the entire mine room face. Upon the cutting of each new entry, coal which has accumulated upon the bottom kerf cutter bars 44 and 45 will be conveyed rearwardly in the conveyer way or trough 49 by the chains 54 and 55 of kerf cutter bars 44 and 45 and the chains of conveyers 265 and 266.

As the machine is sumped into the mine face in the sumping operations described, the cutter bars 309 and 310 are in their lowered positions. However, the machine may be sumped with the cutter bars 309 and 310 in their elevated positions so that their forward portions cut at the plane 431 of the mine room ceiling. When the machine is sumped in this manner the first shear cut made by each of the shear cutter bars 309 and 310 is defined by line or plane 431 on the top and line or plane 438 on the bottom, as seen in Fig. 4. After the machine has been sumped to the proper depth, cutter arms 309 and 310 are lowered to finish cutting the spaced upright shear kerfs 429 and the breakdown mechanism 78 is then operated to break down the coal above the bottom kerfs 427 and between the spaced upright side kerfs 429 in the second manner above described. It will be seen that when the machine is operated in this manner because the rear ends of the cutter bars 309 and 310 are pivoted and their front ends swing to a position lower than the rear ends there will be an area 439 in which the cutter bits of the shear kerf cutter chains do not operate, and, as previously set forth, it appears superficially that a horizontal web or rib of coal will remain in the area 439. However, because of the friable nature of the coal being mined and the vibrations of the machine, the area 439 in which the cutter bits of the side kerf cutter arms 309 and 310 do not operate will generally not form but even in the event they do they are not of sufficient strength to interfere with the coal break down operation.

In addition to performing the cutting and loading operations above set forth the machine is capable of being used purely as a loading machine, that is, the machine may be sumped or driven into an accumulation or pile of loose coal and the cutter and conveyer chains 54 and 55 will then operate to gather and convey the loose coal rearwardly along the conveyer trough or way 49 from which it will be discharged into the receiving hopper 84 and conveyed rearwardly along the boom 87 in the manner previously described.

It is thus evident that I have provided a very flexible and efficient combination coal cutting and loading machine which is entirely self-contained and requires no exterior ropes, jacks or similar equipment.

Obviously those skilled in the art may make various changes in the details and arrangement of parts without departing from the spirit and scope of the invention as defined by the claim hereto appended and I wish therefore not to be restricted to the precise construction herein disclosed.

Having thus described and shown an embodiment of my invention, what I desire to secure by Letters Patent of the United States is:

In apparatus of the class described, a kerf cutter and conveyer means including a pair of laterally spaced rigidly connected cutter bars permanently spaced apart and forming a conveyer way between them, an orbitally moving endless cutter and conveyer chain means on each of said cutter bars adapted to cut a kerf and convey material rearwardly along said way, chain guide means carried by each of said cutter bars, an orbitally moving endless chain conveyer carried by each of said chain guide means adapted to co-operate with the rear portions of said orbitally moving kerf cutter and conveyer chains to convey material rearwardly along said way, said cutter bars and said chain guide means being di-

5

vided between the ends of said chain guide means and connected for swinging adjustment about a horizontal axis, and automatic means for adjusting the lengths of said chain guide means.

NILS D. LEVIN.
